FRANK E. ALLEN.

UNITED STATES PATENT OFFICE.

FRANK E. ALLEN, OF YONKERS, NEW YORK, ASSIGNOR TO ROXBURY CARPET COMPANY, OF BOSTON, MASSACHUSETTS.

DESIGN FOR CARPETS.

Specification forming part of Design No. 10,263, dated October 2, 1877; application filed September 26, 1877.
[Term of Patent 3½ years.]

To all whom it may concern:

Be it known that I, FRANK E. ALLEN, of Yonkers, in the State of New York, have invented a new and original Design for Carpets, of which the following is a specification:

The nature of my design is fully shown in the accompanying photographic illustration.

I claim—

The design for carpets, as shown in the accompanying photographic illustration.

In testimony whereof I have signed my name to this specification in the presence of two subscribing witnesses.

FRANK E. ALLEN.

Witnesses:

C. T. BROWN,
A. E. DENISON.
